US0D1085220S

(12) United States Design Patent (10) Patent No.: US D1,085,220 S
(45) Date of Patent: * Jul. 22, 2025

(54) DETACHABLE COVER

(71) Applicant: HEWLETT-PACKARD DEVELOPMENT COMPANY, L.P., Spring, TX (US)

(72) Inventors: Jongkyu Kim, Seongnam-si (KR); Yoona Min, Seongnam-si (KR); Sangeon Park, Seongnam-si (KR); Hakyung Kim, Seongnam-si (KR)

(73) Assignee: Hewlett-Packard Development Company, L.P., Spring, TX (US)

() Term: 15 Years

(21) Appl. No.: 29/833,437

(22) Filed: Apr. 4, 2022

(51) LOC (15) Cl. 18-02

(52) U.S. Cl. USPC ..... D18/56

(57) CLAIM

The ornamental design for a detachable cover, as shown and described.

DESCRIPTION

FIG. 1 is a right-front-top perspective view of the detachable cover of the present invention, showing a new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is top plan view thereof;

FIG. 7 is a bottom plan view thereof; and,

FIG. 8 is a left-back-bottom perspective view.

The broken lines in the figures show portions of the detachable cover that form no part of the claimed design. The shade lines in the figures show contour and not surface ornamentation.

1 Claim, 6 Drawing Sheets
